(57) **CLAIM**

The ornamental design for an optical network terminal, as shown and described.

DESCRIPTION

FIG. 1 is a perspective view of an optical network terminal showing our new design;

FIG. 2 is a front elevational view thereof;

FIG. 3 is a rear elevational view thereof;

FIG. 4 is left side elevational view thereof;

FIG. 5 is a right side elevational view thereof; and,

FIG. 6 is a top plan view thereof.

The broken lines in the drawing figures are used to define the bounds of the claim and form no part of the claimed design.
